[57] CLAIM

The ornamental design for combined steam iron support and water tank, as shown.

DESCRIPTION

FIG. 1 is a perspective view of a combined steam iron support and water tank showing my new design;
FIG. 2 is a front elevational view thereof;
FIG. 3 is a front elevational view thereof;
FIG. 4 is a rear elevational view thereof;
FIG. 5 is a top plan view thereof;
FIG. 6 is a bottom plan view thereof.
